(57) **CLAIM**

The ornamental design for a door hanger with collar stay card, as shown and described.

DESCRIPTION

FIG. 1 is a front perspective view of the door hanger with collar stay card, showing our new design;

FIG. 2 is a left side elevation view of the design illustrated in FIG. 1;

FIG. 3 is a front view of the design illustrated in FIG. 1;

FIG. 4 is a right side elevation view of the design illustrated in FIG. 1;

FIG. 5 is a top view of the design illustrated in FIG. 1;

FIG. 6 is a bottom view of the design illustrated in FIG. 1;

FIG. 7 is a rear view of the design illustrated in FIG. 1;

FIG. 8 is a front perspective view of the door hanger with collar stay card, showing another embodiment of our new design;

FIG. 9 is a left side elevation view of the design illustrated in FIG. 8;

FIG. 10 is a front view of the design illustrated in FIG. 8;

FIG. 11 is a right side elevation view of the design illustrated in FIG. 8;

FIG. 12 is a top view of the design illustrated in FIG. 8;

FIG. 13 is a bottom view of the design illustrated in FIG. 8; and,

FIG. 14 is a rear view of the design illustrated in FIG. 8.
